(57) **CLAIM**

The ornamental design for a conference webcam, as shown and described.

DESCRIPTION

FIG. 1 is a front perspective view of a conference webcam showing my new design;

FIG. 2 is a rear perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is a perspective view thereof in another unfolded state; and,

FIG. 10 is a perspective view thereof in a folded state.

The broken lines in the drawings illustrate the portions of the conference webcam which form no part of the claimed design.

1 Claim, 10 Drawing Sheets
